Hulbard & Price of St. Johnsbury Vermont.

Lettered Patent

The deliberate refusal to in the Lettered Patent and making final of the same containing a description in the words of the said Hulbard & Price himself of his improvement in the Boot Braces.

To all people to whom these presents shall come. Be it known that of Hulbard & Price of St. Johnsbury in the County of Caledonia and State of Vermont, have invented a new and useful improvement in the Boot Brace, and that the following is a full description thereof. The brace board is to be made of wood or some like substance and is first formed similarly to this in section by a series of several dimensions, proportional to the size of the article, from one to the other of the four let them be cut an inch and an half or more or less in depth extending semicircularly to a point upon the back part of the leg about equidistant from the heel, thereby cutting off the heel as in bending in ordinary use and leaving instead thereof an arc of a circle around each of the centers of the four faces, of which are applied a bedded socket of hard or metallic substance for the point of a screw hereinafter described to play upon as a fastener. Said brace having a moveable heel of iron or other hard or metallic substance to rest upon said arc of a circle and to do its office to play off the front by a screw of metallic or hard substance to pass through the point of the socket to the above named socket. Upon the point of said screw may be wound there or more metallic springs to confine the leather in confining all suitable places. When this leather is to be confined is suitably placed upon the board by means of said spring catch it by some strong screw said moveable heel and suitably at the other parts to keep it in place and then by the power of said screw with little labor the leather will be brought into suitable shape and can just be divided. Said improvement consisting in

and moveable toe heel and the said springs applied to the cramp, in other respects, of ordinary use and is to be known by the name of "the heel-spring Boot Cramp" which improvement I claim as my own invention. A model and drawing accompanying this specification. In testimony that the above is a true specification of my said improvement as above described I have hereunto set my hand this 25th day of April A.D. 1836
